UNITED STATES PATENT OFFICE.

ELLEN V. CONWAY, OF RICHMOND, VIRGINIA, EXECUTRIX OF THE ESTATE OF JAMES H. CONWAY, DECEASED.

IMPROVED MEDICAL COMPOUND.

Specification forming part of Letters Patent No. 55,214, dated May 29, 1866.

To all whom it may concern:

Be it known that JAS. H. CONWAY, late of the city of Richmond, in the State of Virginia, invented a new and useful Compound to be used as a Cough Mixture; and I, ELLEN V. CONWAY, widow and executrix of the said JAS. H. CONWAY, hereby declare the following to be a full and exact description of the said compound and the manner of using it—that is to say:

Take sirup tolu, $\frac{3}{2}$ ii, (two ounces;) acet. morphia, grs. iv, (four grains;) acid acetic gtt. xii, (twelve drops;) chloroform, gtt. xxx, (thirty drops;) em. guin-acac., $\frac{3}{2}$ ii, (two ounces.)

To be used as follows, to wit: The dose for an adult, one tea-spoonful every four hours; for children from eight to ten years, half a tea-spoonful every four hours; from two to eight years, twenty drops every four hours. Shake the bottle before using and keep it closely corked.

Having thus described the invention of the said JAS. H. CONWAY, what is claimed is—

The compound or cough mixture as herein described.

ELLEN V. CONWAY,
Executrix and Sole Devisee of James H. Conway, deceased.
